CLAIM

I claim the ornamental design for a hose for industrial vacuum cleaner, as shown.

DESCRIPTION

FIG. 1 is a perspective view of a hose for industrial vacuum cleaner showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The body of the cleaner is shown in broken lines and is unclaimed subject matter and forms no part of the claimed design or of a specified embodiment thereof.

1 Claim, 6 Drawing Sheets
